Primary Examiner — Mojtaba Tehrani(74) *Attorney, Agent, or Firm* — Lerner, David, Littenberg, Krumholz & Mentlik, LLP(57) **CLAIM**

The ornamental design for a wallet for mobile device, as shown and described.

DESCRIPTION

FIG. 1 is a front view of a wallet for mobile device in accordance with a first embodiment of our invention;

FIG. 2 is a left side view thereof;

FIG. 3 is a right side view thereof;

FIG. 4 is a rear view thereof;

FIG. 5 is a top view thereof;

FIG. 6 is a bottom view thereof;

FIG. 7 is a front left perspective view thereof;

FIG. 8 is a front view of a wallet for mobile device in accordance with a second embodiment of our invention;

FIG. 9 is a left side view thereof;

FIG. 10 is a right side view thereof;

FIG. 11 is a rear view thereof;

FIG. 12 is a top view thereof;

FIG. 13 is a bottom view thereof; and,

FIG. 14 is a front left perspective view thereof.

Any broken lines shown in the figures are for the purpose of illustrating structure that forms no part of the claimed design.
